UNITED STATES PATENT OFFICE.

CLYDE H. FRENCH, OF SHREVEPORT, LOUISIANA.

TUBING ANCHOR FOR PUMPING OIL WELLS.

Application filed January 17, 1922. Serial No. 529,951.

To all whom it may concern:

Be it known that I, CLYDE H. FRENCH, a citizen of the United States, residing at Shreveport, in the parish of Caddo and State of Louisiana, have invented certain new and useful Improvements in Tubing Anchors for Pumping Oil Wells, of which the following is a specification.

This invention relates to wells of the deep pumping type, and the primary object of the invention is to provide a novel means for supporting the well tubing, so as to effectively prevent the dropping of the tubing in the well, in case of breakage or accident.

Owing to the great weight sustained by the top collar of the well tubing and the constant vibration placed thereon due to the pumping operation, the well tubing often breaks at this point and falls into the well.

This, of course, results in loss of time and the trouble and cost of taking the tubing from the well. Very often, if the rig burns down, the tube will drop into the well, and thus cause the same trouble.

It is therefore an important object of the invention to provide a novel tubing anchor which embodies means for engaging the tubing above and below the ordinary casing head, the means for engaging the tubing below the casing head consisting of a slip clamp, which tends to support the weight of the tubing and which will effectively hold the tubing against dropping, if the tubing breaks at the casing head or strips the threads thereof at the collar, which is the weakest point of the tubing string.

Other objects of the invention are to provide in a novel tubing anchor; first, novel means for holding the tubing in position against dropping, which will permit the easy raising of the tubing when desired or necessary; second, to provide a tubing anchor of simple construction which will eliminate the usual tubing and casing ring; and third, to provide a tubing anchor which will effectively prevent the leakage of gas from the well casing and which only requires a single packing in lieu of the multiple packing used in wells of the ordinary construction now in use.

A still further object of the invention is to provide an improved well tubing anchor of the above character, which is durable and efficient in use, one that is simple and easy

to manufacture, and one which can be placed upon the market at a reasonable cost.

With these and other objects in view, the invention consists in the novel construction, arrangement and formation of parts, as will be hereinafter more specifically described; claimed and illustrated in the accompanying drawings, forming a part of this specification, in which drawings:

Figure 1 is a fragmentary longitudinal section through a well casing, showing the improved tubing anchor incorporated therewith, the anchor being shown in elevation.

Figure 2 is a similar view showing the anchor in longitudinal section.

Figure 3 is a horizontal section taken on the line 3—3 of Figure 2, and

Figure 4 is a horizontal section taken on the line 4—4 of Figure 2.

Referring to the drawings in detail, wherein similar reference characters designate corresponding parts throughout the several views, the letter A indicates the improved anchor for effectively supporting and holding a well tubing B in a well casing C, which has connected therewith the casing head D.

The casing head D is of the ordinary construction, and includes the annular body 5, provided at its lower end with interior threads 6 for the reception of the threaded end 7 of the well casing C, which is made up in the ordinary manner. The body 5 of the casing head D is provided with the usual gas outlets 8, in which may be threaded the ordinary lead gas pipes (not shown). The upper end of the body 5 of the casing head D is provided with a counterbore 9, which defines the usual seat 10 for the tubing ring or collar, and the upstanding guard flange 11.

The well tubing B is made up of the usual pipe lengths 15 and is supported by the novel anchor A which will now be described.

The improved tubing anchor A includes a head 16 having the annular flange 17 formed thereon, which is provided with a lower plane face 18. This flange 17 is adapted to snugly rest upon the seat 10, formed in the casing head D, and the plane lower face 18 of this flange is provided with a groove 19 for the reception of a packing ring 20, which is provided for the purpose of preventing the leakage of gas 110

past the head 16 and the casing head D. It is obvious that the packing 20 will be forced into intimate contact with the seat 10, in view of the weight sustained by the head 16 of the anchor. The upper end of the head 16 supports the lift nipple 21, which can be provided with interior threads 22 and 23, for the reception of a lower pipe length 15 of the well tubing B and an upper length 15 of the well tubing as clearly shown in Figure 2 of the drawings. The bore of this nipple 21 is of course, substantially the same as the exterior diameter of the pipe lengths forming a part of the well tubing.

The head 16 supports a depending concentrically disposed supporting sleeve 25, the interior diameter of which is greater than the exterior diameter of the well tubing B, so as to permit the well tubing to be readily moved therein for engaging the lower set of threads 22 formed in the lift nipple 21. The bore of the sleeve 25 has the outer end thereof counter-bored, as at 26, which defines a limiting shoulder 27, the purpose of which will hereinafter more fully appear. The counter bored portion 26 of the sleeve 25 is provided with interior threads 28, for the reception of the threaded portion 29 of the collar adjusting slip 30. The threaded portion of the adjusting collar is reduced in diameter, as clearly shown in Figure 2 of the drawings, and the interior surface of the reduced portion 35 is gradually flared outwardly as at 30' to receive the slip clamp 31. This slip clamp 31 consists of a split ring 32, the outer surface of which is tapered or wedge shaped. The inner surface of the ring 32 is preferably provided with serrations or teeth for gripping the well tubing B. The lower end of the adjusting slip collar 30 is provided with a nut face 34 by means of which the collar may be readily turned by a wrench for adjusting the slip clamp into intimate contact with the well tubing.

It is obvious that when the adjusting slip collar 30 is rotated and threaded into the sleeve 25, the tapered inner face 28 thereof will be forced into contact with the outer tapered face of the slip clamp 31, which will force the slip into biting contact with the well tubing B. Upward movement of the slip clamp is prevented in the sleeve 25, owing to the fact that the slip clamp is adapted to seat upon the collar 27.

In use of the improved anchor, the upper end of the tubing is first inserted into the lift nipple 21, after which the adjusting collar 30 is turned so as to force the slip clamp into engagement with the tubing. The nipple 21 and the whole anchor is then lowered, until the flange 17 rests upon the seat 10 and the weight of the tubing will

compress the gasket 20 as heretobefore stated, and form a leak proof joint between the anchor and the well casing head D.

From the foregoing description, it can be seen that an improved anchor has been provided for the well tubing, which provides means for supporting the tubing below the casing head, and which forms an intimate seating contact between the casing head, so as to prevent the leakage of gas from the casing, and thus entirely eliminate the necessity of providing a plurality of different packings as now utilized in well pump casings of the ordinary type.

Changes in details may be made without departing from the spirit or scope of this invention; but, I claim:

1. In a well, the combination with a casing and well tubing, and a head for the casing and well tubing, of an anchor connected to the well tubing at its upper end and including means for engaging the casing head, and a clamp carried by the anchor for engaging the well tubing at a point below said casing head and remote from the first mentioned connection of the anchor and tubing.

2. In a well pump, the combination with a casing, a head carried by the upper end of the casing provided with a seat, and a well tubing disposed concentrically within the casing, of an anchor connected to said tubing adjacent said head including a head disposed upon said seat, a depending sleeve formed on the anchor head terminating in a plane below the casing head, and an adjustable clamp carried by the lower end of the sleeve for engaging said well tubing at a point below said casing head and remote from the first mentioned connection of the anchor and tubing.

3. The combination with a well casing, a head for said casing provided with a seat at its upper end, and a well tubing disposed in said casing, of an anchor for the well tubing including a head arranged to fit on the seat in the casing head, said anchor head being provided with interior threads at its upper end for the reception of a portion of the well tubing, a depending sleeve formed on the head of the anchor extending below the casing head, a slip clamp disposed in the lower end of the sleeve for engaging the well tubing at a point below said casing head and remote from the first mentioned connection of the anchor and tubing, and an adjustable collar carried by the sleeve for engaging said slip.

4. The combination with a well casing, a head carried by the upper end of the casing having a seat formed on its upper end, and a well tubing disposed in said casing, of an anchor for said tubing including a head having an outwardly extending flange formed thereon arranged to sit upon the seat

formed on the casing head, a lift nipple formed on the upper end of the anchor head provided with interior threads for the reception of the well tubing, a depending sleeve formed on the lower end of the head extending into the casing below the casing head and having an interior diameter greater than the exterior diameter of the tubing, the lower end of the sleeve being enlarged 10 interiorly and defining a shoulder and provided with threads, a split ring fitted in the enlarged portion and against said shoulder and provided with interior teeth for

engaging said tubing at a point remote from said first mentioned connection of the anchor 15 and tubing, the outer face of said split ring being tapered, and an adjustable collar threaded into the threaded portion of the sleeve having a tapered inner face for engaging said ring for forcing the same into 20 intimate contact with the tubing and including a polygonal shaped wrench head extending outwardly from the said depending sleeve.

CLYDE H. FRENCH.
